UNITED STATES PATENT OFFICE.

SOLOMON H. RITTER, OF POTTSGROVE, PENNSYLVANIA.

PLOW ATTACHMENT.

SPECIFICATION forming part of Letters Patent No. 606,244, dated June 28, 1898.

Application filed November 5, 1897. Serial No. 657,529. (No model.)

To all whom it may concern:

Be it known that I, SOLOMON H. RITTER, a citizen of the United States, residing at Pottsgrove, in the county of Northumberland and 5 State of Pennsylvania, have invented a new and useful Plow Attachment, of which the following is a specification.

My invention relates to improvements in attachments for plows by which the width of 10 the furrow may be regulated by a variation in the position of the beam; and the object that I have in view is to provide a simple means for adjusting the beam, which adjusting means is capable of ready application to 15 the plow and is adapted to be operated by the driver without leaving his position at the handles of the implement.

With these ends in view my invention consists in the combination, with a stock and 20 handles of a plow, of a pivoted beam, a fixed bracket arranged between and attached to the handles and provided at one end with a loop and in its straight length with a longitudinal slot, a worm or screw shaft journaled 25 in the bracket, a traveling nut attached to the plow-beam and fitted to engage with the worm or screw shaft, a lever for imparting motion to the shaft, and means for locking the lever, shaft, and plow-beam in their ad- 30 justed positions, substantially as will be hereinafter fully described and claimed.

The invention further consists in the construction and arrangement of parts, which will be more fully pointed out, and then de- 35 fined in the claims.

To enable others to understand the invention, I have illustrated the same in the accompanying drawings, forming a part of this specification, in which—

40 Figure 1 is a perspective view of a plow equipped with my regulating attachment. Fig. 2 is a plan view. Fig. 3 is a detail sectional view taken through a part of the plow-beam, the traveling nut, and the worm or screw shaft on the plane indicated by the dotted line 3 3 of Fig. 2. Fig. 4 is a rear elevation of my attachment, showing a part of the plow-handles and the plow-beam.

Like numerals of reference denote corre- 45 sponding parts in all the figures of the drawings.

According to my present invention it is necessary to mount the plow-beam 1 pivotally upon the stock or foot 2 of an ordinary plow. The pivotal attachment of the beam to the 55 stock or foot may be effected in any suitable way by a skilled mechanic; but in the drawings I have shown the pivotal bolt 3 as one means for adjustably connecting the plow-beam to the foot or standard 2. This pivotal connection of the plow-beam to the standard is effected at a point intermediate of the length of the plow-beam, thus leaving the rear end of said beam free for the application 60 of the device for adjusting the beam to vary the position thereof to regulate the width of the furrow.

In all essential particulars except the pivotal attachment of the beam to the foot or standard 2 the plow is similar to ordinary 70 plows in use, and my attachment is adapted for use in connection with such ordinary plows by a few changes in the parts thereof.

Between the handles 4 of the plow is arranged a bracket 5, which is constructed in a 75 peculiar manner to serve as a guide for a traveling nut, to provide for its attachment to the plow-handles, and to receive the adjusting and fastening devices for the worm or screw shaft, all forming a part of the attachment. 80 This bracket 5 consists of a straight length or shank 6 and a loop-shaped end 7, which are made in a single piece of metal, and at one end the straight shank 6 of the bracket is formed with a threaded tenon 8, adapted 85 to be inserted in an aperture in one of the plow-handles. The angular or looped end of the bracket is adapted to be applied against one of the plow-handles, while the threaded tenon at the other end of the bracket fits in 90 the other handle. The bracket is secured in position by bolting the angular or looped end 7 to one handle and by applying a nut to the threaded tenon 8 or by heading this tenon against the handle. The bracket is thus 95 adapted to be secured firmly in place between the handles for its straight shank 6 to occupy a horizontal position below the rear end of the plow-beam, while the angular or looped end 7 of the bracket drops downwardly or below 100 the level of the straight shank of the beam. The straight shank 6 of the bracket is pro-

vided with a longitudinal slot 9, which forms a guide for the traveling nut 10. This traveling nut is arranged to lie below the straight shank of the bracket to be guided therein, 5 and said nut has a vertical stem 11, which passes through the slotted shank of the bracket, the upper end of said stem fitting in an aperture 12 in the rear free end of the pivoted beam. The upper extremity of the stem 10 of said traveling nut is threaded to receive a nut 13, which bears on the washer or wear-plate 14, which rests on the beam, and thus the stem of the traveling nut is attached to the beam to insure movement of the beam 15 when the nut is actuated by the worm or screw shaft 15. This worm or screw shaft occupies a horizontal position below the straight shank of the bracket 5, and one end of the shaft has a journal 16, which passes through 20 an opening or bearing 17, formed in one of the arms of the angular or loop-shaped end 7 of the bracket, while the other end of the worm or screw shaft is provided with a journal 19, that fits in a bearing-plate 18, which 25 is confined between one of the plow-handles and the tenon 8 of the bracket 5.

The journal 16 of the worm or screw shaft 15 projects into the angular or looped part of the bracket 5, and on this journal is mounted 30 a ratchet-disk 20 and an operating-lever 21. The ratchet-disk 20 is secured rigidly to the journal 16 of the screw-shaft in any suitable manner—as, for instance, by a key or a set-screw—so that the ratchet-disk is adapted to 35 turn with the screw-shaft; but the lever 21 is fitted loosely on said journal of the screw-shaft in order that the lever may be operated back and forth as required to impart rotary motion to the ratchet and the screw-shaft for 40 the purpose of adjusting the traveling nut and the plow-beam.

The free protruding end of the journal 16 is threaded to receive a nut 22, between which and the side of the lever 21 is interposed a 45 washer 24, said nut and washer serving to hold the lever against displacement on the journal of the worm or screw shaft and in proper operative relation to the ratchet-wheel. This lever is provided with a loose double- 50 acting pawl 25, which is hung or pivoted on the lever, as at 26, in a position for one or the other of the prongs of the pawl to engage with the ratchet-teeth.

Rigidly mounted on the straight horizontal 55 shank of the bracket adjacent to the lever is a perforated or notched segment 27, and on the lever 21 above the pawl 25 is pivoted a thumb latch-lever 28, which is normally pressed by a spring 29 to have its nose engage 60 with one of the perforations or notches in the holding-segment 27, whereby the lever, the ratchet, the worm or screw shaft, and the

nut may be held fixed in their adjusted positions.

The lever of the adjusting attachment may 65 be operated to turn the notched or ratchet disk in either direction for the purpose of turning the worm or screw shaft according as it is desired to adjust the plow-beam one way or the other to widen or narrow the fur- 70

The attachment is simple in construction, cheap of manufacture, easily applied to a plow, and readily adjusted according to the requirements of the service. 75

It is evident that changes in the form and proportion of parts and in the details of construction of my invention may be made by a skilled mechanic without departing from the spirit of the invention. 80

Having thus fully described the invention, what I claim as new, and desire to secure by Letters Patent, is—

1. The combination with plow-handles, and a pivoted beam, of a bracket fixed to said handles and having a slotted shank and a looped end, a worm or screw shaft journaled in the bracket and having one end extended into the looped end thereof, a traveling nut having a stem which passes through the slotted bracket 90 and is attached to the beam, a notched disk or ratchet attached to the protruding end of the worm-shaft, an adjusting-lever fitted loosely on the end of the worm-shaft, a pawl on said lever, a holding-segment carried by 95 the bracket, and a thumb latch-lever, substantially as and for the purposes described. 85

2. The combination with a pivoted plow-beam, of a fixed bracket, a traveling nut slidably fitted to the bracket and attached to 100 the plow-beam for moving the latter on its pivot, a worm-shaft passing through the nut and journaled in the bracket, and means for rotating and locking the screw-shaft, substantially as described. 105

3. The combination with a plow-beam pivoted to turn on a vertical axis, of a fixed bracket on a plow-frame, a traveling nut slidably fitted to the bracket and connected with the beam by a vertical pivot parallel to 110 the beam-pivot, a screw-shaft passing through the nut and journaled in the bracket, a ratchet on the screw-shaft, an adjusting-lever carrying a feed-pawl and a locking device, and a fixed segment on the bracket with which the 115 lever-locking device is engaged, substantially as described.

In testimony that I claim the foregoing as my own I have hereto affixed my signature in the presence of two witnesses.
